ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA

FILLING CONTAINERS WITH LIQUID

Application filed February 20, 1929. Serial No. 341,313.

My invention relates to the art of filling containers with liquid. The particular embodiment of the invention herein shown and described for purposes of illustration is adapted for use in the canning art, as a syruper, but it is to be understood that the invention may be applied to the filling of any containers with liquid to a predetermined level.

The object of the invention is to provide a method and apparatus for filling containers which can be embodied in a machine of simple construction, capable of continuous and rapid operation, and which fills each container automatically to a predetermined level without waste or spilling of the liquid. Other objects and advantages of the invention will become apparent from the following description, which should be read with the understanding that the method involved in the invention may be embodied in apparatus other than that shown and described herein, and that the form, construction and arrangement of the several parts of the described apparatus may be varied, within the limits of the claims hereto appended, without departing from the spirit of the invention as set forth therein.

The invention is preferably embodied in a machine having a rotating can carrying turret adapted to continuously advance a procession of cans in a circular path, during which movement the cans are successively filled with liquid. The liquid first fills the can completely, and its level is subsequently lowered to a predetermined point by the tilting of the can, thereby causing the excess liquid to flow out of the can and return to the liquid containing reservoir. The construction of a machine embodying the invention in the preferred form will now be described with reference to the accompanying drawings, wherein:—

Fig. 1 is a partly broken side elevation, the cans and the details of the filling valves being omitted for the sake of clearness.

Fig. 2 is an elevation of the machine as seen from the opposite side.

Fig. 3 is an enlarged sectional detail of the

filling valve showing a can in filling relation thereto.

Fig. 4 is a view similar to Fig. 3 showing the valve in closed position.

Fig. 5 is a diagrammatic development of the path of travel of a can through the machine.

In the drawings, the reference numeral 1 designates a base from which rises an inclined central shaft or spindle 2. Upon said shaft are rotatably mounted a turret 3 and a superposed liquid containing tank or reservoir 4. The turret 3 and the tank 4 are connected by suitable braces or frame members 5 so that they are held in fixed relation to each other and rotate together. The turret 3 is shown as provided with a ring gear 6 by which both it and the tank 4 are rotated about the central spindle 2 by any suitable means, not shown.

Because of the fixed inclination of the central spindle 2, the turret 3 and the tank 4 rotate in planes inclined from the horizontal, as shown clearly in Figs. 1 and 2. The turret 3 carries a series of evenly spaced guide members 7, in each of which is a longitudinally slidable can holder comprising a shank 8 and a head 9, the shank extending into the guide 7, and the head 9 being adapted to support and hold a can 10, as shown in Figs. 3 and 4. As an example of a suitable means for holding the can securely upon the head 9, I have shown the latter as provided with under-cut guide flanges 11 adapted to engage the flange or rim 12 upon the lower end of the can. One side of the head 9 is open, as shown, to permit the can to be slid horizontally in and out.

The can holders are raised and lowered in their guides 7, as the turret revolves, by means of a stationary cam 13 formed upon or carried by the base 1. Each holder shank 8 has a pin 14 projecting through a slot 15 in the guide 7 and carrying a roller 16 adapted to ride upon the cam 13. For the greater part of its circumference, the cam 13 lies in a plane parallel to the plane of rotation of the turret 3, but upon one side of the machine, as shown in Fig. 1, said cam has an abrupt depression 13a followed by a horizontal portion 13b,

which returns to the inclined plane of the remainder of said cam. The turret is assumed to rotate from right to left in Figs. 1 and 2. The guides 7 are angularly related to the plane of the turret 3 in such a manner that the can holder whose roller 16 is travelling upon the horizontal portion 13b of the cam is approximately vertical, as indicated at the position "B" of Fig. 1. It will be seen that the can holder is exactly vertical only at one position in the revolution of the turret, this position occurring about the center of the horizontal portion 13b of the cam. It will also be seen that any given can holder, as it is carried around by the rotation of the turret, is moved toward and away from the bottom of the tank 4 in addition to being carried through a continuously varying angle of inclination from the vertical. Thus at the position "A", Fig. 1, the holder is farthest removed from the bottom of the tank 4, and is almost vertical. From this position to the position "C", said holder approaches the tank 4 and passes through its vertical position at "B". From the position "C" to the position "D" the holder remains at the same distance below the tank 4, but is lower in space because of the inclined travel of the turret 3. From the position "D" around to the position "F", i. e. through a travel of 180 degrees, the holder remains in the same relative position to the tank 4, but is elevated in space, and its inclination is first increased and then decreased, reaching a maximum about the point "E", Fig. 2, which is approximately opposite the point "B" of Fig. 1. From "F" to "A" the holder recedes away from the bottom of the tank 4 and its inclination approaches the vertical. These various positions of the can are also shown in the diagram of Fig. 5, which is a development of the path of the can, showing its relation to the tank 4 in its various positions. As in Figs. 1 and 2, the can is assumed to move from right to left.

In the bottom of the tank 4 are a plurality of valves, indicated conventionally at 17' in Figs. 1, 2, and 5, one positioned in longitudinal alignment above each can holder. These valves are, of course, inclined with respect to the bottom of the tank, their inclination corresponding respectively with that of the can holders carried by the turret. One valve is shown in detail in Figs. 3 and 4, and a description thereof will suffice for all. The bottom of the tank 4 is provided with an inclined flanged aperture 17, to which is bolted, inside the tank, a spider 18. A flexible annulus 19 formed of rubber or other suitable resilient material is clamped between the flange of the aperture 17 and the base of the spider 18.

The spider 18 carries a central hollow stem 20 upon the lower end of which is a head 21 slightly concave on its under surface. The aperture of said stem 20 communicates with

a vent tube 22 which extends upwardly to the top of the tank above the level of the liquid therein. A ring 23 is carried by pins 24 slidably mounted in the spider 18, and is pressed downwardly upon the top of the flexible annulus 19 by means of springs 25. In its normal position, the annulus 19 bears against the upper surface of the head 21, as shown in Fig. 4, in which position the valve is closed and no liquid can escape from the tank. When, by reason of the upward movement of the can holder 9, the can 10 is elevated against the annulus 19, said annulus is raised away from the head 21, as shown in Fig. 3, thus allowing the liquid to flow from the tank 4 into the can. The contact of the edge of the can with the annulus 19 prevents any spilling of the liquid, and the vent 22 allows the air from the can to escape as the liquid flows into it. If the can contains any solid matter, such as pieces of fruit, the head 21 bears lightly upon the top thereof, holding the same in place during the tilting of the can.

Referring again to Figs. 1 and 5, the full cans are successively removed from the holders 9 and the empty cans placed thereupon at or between the positions "A" and "B", either manually or by any suitable mechanism, not shown in the drawings. In this region of the travel of the can holder, it is approximately vertical, and is lowered so that the can is entirely clear of the filling valve, as shown in Fig. 4. When the can is elevated by its holder into contact with the valve, which condition occurs at the position "C" and continues until the position "F" is reached, i. e. for about three-quarters of a revolution, the valve is held open, as shown in Fig. 3, and the can is in free communication with the interior of the tank 4.

The level of the liquid within the tank is maintained constant by any suitable mechanism, such for example as that illustrated in Fig. 1, comprising a valve indicated at 26 operated by a float 27. said valve controlling the liquid supply pipe 28, which is adjustably carried by the spindle 2. A screw 29 operating in flanges 30 secured to said spindle and threaded through a collar 31 secured to the liquid supply pipe 28 and slidable upon the spindle 2, provides a means for raising or lowering said pipe and the valve 26 and thereby adjusting the level of the liquid within the tank 4.

The level of the liquid within the tank, as indicated by the line 32 in Figs. 1 and 5, is maintained at such a position that the valves in the bottom of said tank are below said level for a part of their travel and above it for the remainder thereof. The effect of this condition is to cause the liquid to flow into the can from the time it passes the position "C" until it reaches an approximately opposite position, upon the other side of the machine, as indicated at "E" in Fig. 5. From

this position to the position "F", the valve is above the level of the liquid in the tank 4, and, the can being inclined, a portion of the liquid which has previously flowed into it, flows out again back into the tank. This flow of the excess liquid back to the tank continues until stopped by the lowering of the liquid in said can and the decreasing inclination thereof. Then as the can is again righted to a vertical position, the level of the liquid within it is at a predetermined distance below its top, such distance being determined by the maximum inclination of the can after its valve emerges from beneath the level of the liquid in the tank, which is easily adjusted by changing the level of the liquid in the tank by raising or lowering the float valve 26. The final level of the liquid in the can is also affected by the size or thickness of the head 21 in the valve, which acts as a displacement body in the can.

It will be seen that the inclination of the axis of the machine enables me to make use of the comparatively simple rotary principle, and still drain off the excess liquid from the cans by tilting them. Moreover, the tilting of the cans, whereby such drainage is effected, is produced automatically as a natural result of the inclined rotation of the turret, without necessitating any additional mechanism, and the drained excess liquid returns directly to the tank from which it came, without waste or spilling.

The simplicity of the machine will be apparent. The only moving parts are the rotary turret and tank, the slidable can holders, and the flexible annuli in the filling valves. By inclining the axis of the turret, and inclining the can holders with respect to said axis, I am able to place a can in the machine in a vertical position, to avoid any possible spilling of its solid or other contents; raise said can into filling relation with the filling valve; lower the can and valve below the level of the liquid in the tank, so that it is filled by gravity; raise said can and valve above said liquid level and tilt them to drain the excess liquid back into the tank; and finally restore the can to a vertical position in which it can be removed from the machine without spilling its contents. All these operations are performed by the few moving parts mentioned above, during and as a result of the rotation of the turret. The speed of the machine is limited only by the time required for feeding and discharging the cans.

The final level of the liquid in each can is always the same, and can be easily adjusted by raising or lowering the float valve 26.

It is to be noted that, once the can has been placed in contact with the filling valve 17' in the bottom of the tank 4, there is no further relative movement between the can and the tank until said can is removed from the filling valve 17' preparatory to its discharge from

the machine. The can and the tank therefore maintain a fixed relation during the greater part of the revolution of said tank. During such movement of the tank, however, the movement of the can, in space, is a compound one, involving continuous shifting and changing inclination of its axis, and lowering and raising with respect to the liquid level in the tank. The result of this compound motion is a twisting and rolling of the can, both during the filling of liquid thereinto and the overflow of the excess therefrom. If the can contains solid matter, such as whole fruit or pieces thereof, this twisting and rolling of the can is of great advantage in that it gently shifts the solid portion of the can contents, thereby preventing the formation of air pockets under or between pieces of such solids.

The twisting and rolling motion of the can, while maintained in fixed relation to the tank, is caused by the inclination of the tank axis and the additional inclination of the can axis relative to said tank axis. This relative inclination of the can axis, it will be noted, is in a plane tangential to the tank, and not radial thereto, and causes the can to pass through a vertical or substantially vertical position, at one point only, about midway between its highest and lowest points in the rotary travel of the tank, viz:—the position B of Fig. 1.

I claim:—

1. The method of filling and draining containers with liquid which consists in positioning a container below a confined body of liquid; then rotating the container bodily about an inclined axis, causing the top of the container to pass first below and then above the level of said body of liquid, the axis of the container maintaining constant angular relation with the axis of rotation and being substantially vertical at the point of positioning.

2. The method of filling and draining containers with liquid which consists in positioning a container below a confined body of liquid; then rotating the container bodily about an inclined axis, causing the top of the container to pass first below and then above the level of said body of liquid; establishing communication between the container and the body of liquid during said rotation, the container remaining outside the body of liquid during said rotation and its axis maintaining constant angular relation with the axis of rotation.

3. An apparatus of the character described comprising a movable liquid containing tank having a discharge aperture; means for holding a container in filling relation thereto; and means for moving said tank and said container without change in relative position in an inclined orbital path which causes the axis of said container to lie in a vertical plane of continuously changing horizontal angularity.

4. An apparatus of the character described

comprising a movable liquid containing tank having a discharge aperture; means for holding a container in filling relation thereto; and means for moving said tank and said container without change in relative position in a path which causes the axis of said container to continuously shift its inclination in a vertical plane, which plane is continuously changing its own horizontal angularity.

5. An apparatus for the described purpose comprising a liquid containing tank rotatable about an inclined axis; can receiving seats angularly mounted in the bottom of said tank, the angularity of said seats causing them to lie in a substantially horizontal plane at one point in the rotation of said tank; and means for moving containers into and out of filling relation with said seats.

6. An apparatus for the described purpose comprising a liquid containing tank rotatable about an inclined axis; can receiving seats angularly mounted in the bottom of said tank, the angularity of said seats causing them to lie in a substantially horizontal plane at one point in the rotation of said tank; means for holding open top containers and moving them into and out of contact with said seats while said seats are substantially horizontal; and means for establishing communication between the tank and the containers in contact with said seats.

7. An apparatus for the described purpose comprising a liquid containing tank rotatable about an inclined axis, said tank having a discharge aperture positioned to travel in a path lying partly below and partly above the level of the liquid in said tank; and means for positioning a container to be filled in free filling relation with said aperture, and for maintaining the relative positions of said tank and said container unchanged during the rotation of said tank.

8. An apparatus for the described purpose comprising a liquid containing tank rotatable about an inclined axis and provided with a discharge aperture positioned to travel in a path lying partly below and partly above the level of the liquid in said tank; a holder adapted to receive and hold a container to be filled with its axis inclined with respect to said tank axis, said holder being rotatable with said tank; and means for moving said holder to carry the container into and out of filling relation with said aperture without change in the relative angular relation between said axes.

9. An apparatus for the described purpose comprising a turret rotatable about an inclined axis; a tank rotatable and coaxial with said turret and spaced above it; a holder adapted to receive and hold a container to be filled with its axis inclined with respect to said tank axis, said holder being movably carried by the turret; means for raising and lowering said holder during the rotation of

said turret to move the container axially into and out of filling relation with the tank; and a discharge valve in said tank operated by the raising and lowering of the container by said holder.

10. An apparatus for the described purpose comprising a turret rotatable about an inclined axis; a tank rotatable and coaxial with said turret and spaced above it; a guide mounted upon said turret at an incline to the plane thereof; a holder adapted to receive a container to be filled, said holder being slidably carried in said guide; a stationary cam track coaxial with the turret; a cam follower carried by said holder and adapted to raise and lower the container held thereby into and out of filling relation with the tank; and means for establishing free flow of liquid between the tank and the positioned container.

11. An apparatus for the described purpose comprising a turret rotatable about an inclined axis; a tank rotatable and coaxial with said turret and spaced above it; a holder adapted to receive a container to be filled, said holder being movably carried by said turret and inclined with respect to the axis thereof to position said container substantially vertically at one point in the rotation of said turret; means for raising and lowering said holder during the rotation of the turret to carry the container into and out of filling relation with the tank, said holder being lowered while the container is passing its vertical position; and means for establishing free flow of liquid between the tank and the positioned container, the rotation of the tank and turret carrying said container successively below and above the level of the liquid in said tank.

12. An apparatus for the described purpose comprising a liquid containing tank rotatable about an inclined axis and provided with a discharge aperture, means for positioning a container to be filled in filling relation to said aperture with its axis inclined with relation to said tank axis, and means for maintaining the axes of said container and said tank in fixed angular relation during the rotation of the latter.

13. An apparatus for the described purpose comprising a liquid containing tank rotatable about an inclined axis and provided with a discharge aperture in its bottom, means for positioning a container to be filled in free filling relation to said aperture with the upper end of said container in close contact with the bottom of said tank, and means for maintaining a fixed relation between said container and said tank, said discharge aperture being carried successively below and above the level of the liquid in said tank by the rotation thereof.

14. An apparatus for the described purpose comprising a liquid containing tank rotatable about an inclined axis and provid-

ed with a discharge aperture in its bottom, said aperture being carried successively below and above the level of the liquid by the rotation of said tank, and means for holding 5 a container to be filled in filling relation to said aperture with its axis angularly related to the axis of said tank.

15. An apparatus for the described purpose comprising a liquid containing tank rotatable about an inclined axis and provided with a discharge aperture in its bottom, said aperture being carried successively below and above the level of the liquid by the rotation of said tank, a holder rotatable with said tank, said holder being formed and positioned to receive a container to be filled, and to hold said container with its axis permanently angularly related to the axis of the tank and passing through a vertical position at one 20 point in the rotation of the tank, and means for moving said holder to carry the container into filling relation with said discharge aperture and to maintain it in such relation throughout the rotation of the tank except 25 when the axis of the container is substantially vertical.

16. An apparatus of the character described comprising a liquid containing tank rotatable about an inclined axis and provided with a 30 container actuated discharge valve in its bottom, said valve being carried successively below and above the level of the liquid by the rotation of the tank, and means for placing a container to be filled into operative relation 35 with said valve.

17. An apparatus of the character described comprising a liquid containing tank rotatable about an inclined axis and provided with a container actuated discharge valve 40 in its bottom, said valve being carried successively below and above the level of the liquid by the rotation of the tank, means for placing a container to be filled into operative relation with said valve, said placing means 45 holding said container with its axis so disposed that the container assumes a vertical position during a portion of its travel.

18. An apparatus of the character described comprising a liquid containing tank 50 rotatable about an inclined axis and provided with a discharge aperture in its bottom, said aperture being carried successively below and above the level of the liquid by the rotation of the tank, and means for holding a container 55 adjacent said aperture whereby it is filled during its travel below the liquid level and a portion of the liquid returned to the tank when said container and aperture are above the liquid level.

60 19. An apparatus of the character described comprising a liquid containing tank 65 rotatable about an inclined axis and provided with a container actuated discharge valve in its bottom, said valve being carried successively below and above the level of the

liquid by the rotation of the tank, means for holding a container and moving it into operative relation with said valve, and means for rotating the tank and holding means in unison. 70

20. An apparatus of the character described comprising a liquid containing tank rotatable about an inclined axis and provided with a container actuated discharge valve in its bottom, said valve 75 being carried successively below and above the level of the liquid by the rotation of the tank, means for holding a container and moving it into operative relation with said valve, and means for rotating the tank and holding 80 means in unison, said holding means being positioned to hold said container with its axis so disposed that the container assumes a vertical position during a portion of its travel.

In testimony whereof I have signed my 85 name to this specification.

ALBERT R. THOMPSON.
